UNITED STATES PATENT OFFICE

ERNEST E. PETERSON, OF SOUTH HIBBING, MINNESOTA

TAMPING DEVICE

Application filed November 1, 1928. Serial No. 316,400.

This invention relates to a tamping device particularly adapted for use upon the road beds of railways to tamp beneath and at the sides of the ties.

5 It is my object to provide an attachment for a tamping machine which is designed to operate more rapidly and efficiently to tamp the road bed at both sides and beneath a tie simultaneously while avoiding lateral displacement of the tie. Other objects will appear and be more fully pointed out in the following specification and claims.

In my Patent No. 1,684,109, dated September 11, 1928, I have described and claimed a 15 machine for tamping the road bed between ties and the present invention may be used to advantage with the machine of that patent. Many of the tamping machines heretofore provided tamp the road bed only between 20 ties and such machines often shift the ties laterally out of proper position and leave the material beneath the ties in loose, untamped condition. The present invention is designed to overcome these difficulties and to 25 perform mechanical tamping which resembles the manual tamping where two men work simultaneously at opposite sides of each tie, driving the tamping tools beneath the ties.

In the accompanying drawings which illustrate the best form of my device at present known to me, Figure 1 is a side elevation of the invention attached to a tamping machine of the type described in my above identified patent; Fig. 2 is an enlarged central vertical 35 section through the device detached from the machine and showing its relation to a rail and tie, as in operation; Fig. 3 is a horizontal section taken on the line 3—3 of Fig. 2; Fig. 4 is a vertical section taken on the line 4—4 40 of Fig. 2; Fig. 5 is a perspective view of one of the tamping blades; Fig. 6 is a detail, side view of a suitable supporting sleeve for the tamping blades and Fig. 7 is a section taken on the line 7—7 of Fig. 4.

45 An upright shaft 8 is arranged to be given vertical reciprocating movement by a suitable power driven machine 9, the machine illustrated being like that described in my Patent No. 1,684,109. The lower end of the shaft 8 50 is slidable longitudinally in a sleeve 10 which

pivots supports a pair of tamping blades 11. Each of the blades 11 consists of a metal plate of substantial width and sufficient rigidity to maintain its bent form. The blades 11 have pivot bearings upon a pair of 55 rods 12. Arcuate central portions of the rods 12 engage the sleeve 10 between a pair of flanges 13 and the ends of the rods 12 project at the side edges of the blades 11 and are connected together by a pair of cross 60 members 14, as best shown in Figs. 3 and 4.

Above the rods 12 the blades 11 are bent outwardly to form arms 15, the upper ends of which are joined by toggle members 16 to a sleeve 17 fixed on the shaft 8. Rigid reinforcing members 11^a extend obliquely between the arms 15 and outer extremities of the blades 11, being fixed at their upper ends on the arms 15 and at their lower or outer ends upon the blades 11. Confined between the 70 bottom of the sleeve 17 and upper flange 13 on the sleeve 10 is a coiled spring 18, adapted to normally support the tamping blades 11 in the elevated or retracted position shown in Fig. 2. Beneath the lower flange 13 and secured to the sleeve 10 is a second coiled 75 spring 19 of somewhat stiffer construction than the spring 18. A shoe 20 is fastened to the lower end of the spring 19 to engage the upper surface of the tie 21 adjacent to and beneath which the road bed 22 is to be tamped.

As illustrated, I have shown my invention in connection with the tamping machine 9 supported upon rails 23 which are mounted in the usual manner upon the ties 21. This 85 machine 9 has a power driven shaft 24 operating an eccentric wheel 25. Encircling the wheel 25 is a band 26 pivotally connected at its upper periphery with a tamping arm 27. A pivot shaft 28 supports one end of the arm 27 and the other end of said arm is operatively connected with the upright shaft 8. The pivot shaft 28 may be raised and lowered to adjust the height of the tamping shaft 8 by 90 means of a lever 29, as in the machine of my above identified patent. A suitable guide 30 is provided for the shaft 8. It will be evident that a number of the tamping shafts 8 with associated operating and tamping mecha- 100

nisms, may be provided upon the machine 9 as in the machine of my prior patent.

Operation

In operation, when the road bed 22, adjacent to and beneath a tie 21, is to be tamped, the machine 9 is moved to a position where the shoe or shoes 20 are above the tie 21 and then the pivot shaft 28 is raised so as to lower the shoe 20 into contact with the tie. The tamping blades 11, which are normally in the elevated position shown in Fig. 2, are now placed in operation by rotating the shaft 24. This, through the eccentric wheel 25 and band 15 26, imparts oscillating movement to the arm 27 and vertical reciprocating movement to the shaft 8. As the shaft 8 starts downward, the sleeve 10 is held against movement by the spring 19 and shoe 20 resting upon the tie 20 21 so that the lower end of the shaft moves downward within the sleeve. During this stroke the spring 18 is compressed and the toggle members 16 are actuated to pivot the blades 11 on the rods 12. The operating 25 edges of the blades are thus thrust downward and toward each other, passing beneath the tie 21 at opposite longitudinal sides thereof. When the blades have reached their inner extremity of movement and upon the return 30 stroke of the shaft 8, the spring 18 operates to withdraw the blades 11 from a position like that indicated in Fig. 1 and to return them to retracted position, shown in Fig. 2. The operation is repeated upon the next downward stroke.

In this manner it will be evident that the road bed is simultaneously tamped at both longitudinal sides and beneath the tie upon each downward thrust of the shaft 8. There 40 is no tendency to move the tie and it is held and the position of the tamping members determined by the shoe 20 engaging the upper surface of the tie. The spring 19 operates to compensate for any irregularities and non-uniformities in the ties. It also relieves possible excessive strains on the mechanism and allows the sleeve 10 to move downward in the event that a blade 11 strikes an immovable 45 50 obstacle during the tamping stroke. The tamping with my machine closely resembles in thoroughness the best manual work which has heretofore been performed by pairs of men simultaneously tamping along opposite sides and beneath each tie.

Having described my invention, what I claim as new and desire to protect by Letters Patent, is:

1. In a tamping device an upright shaft for longitudinal reciprocating movement, a member carried by the lower end of said shaft adapted to rest upon a relatively stationary support above the material to be tamped, a pair of tamping blades having operating edges movable downward and toward each other beneath said support and means oper-

able by said shaft and connected to said blades for imparting oscillating movement to said blades.

2. In a tamping device for railway ties, an upright shaft for longitudinal reciprocating movement, a sleeve on the lower end of said shaft, means for supporting said sleeve to permit movement of said shaft therein, a pair of tamping blades pivotally connected to said sleeve and having operating edges movable downward and toward each other beneath said tie and means operable by said shaft for imparting oscillating movement to said blades, said shaft being slideable longitudinally in said sleeve.

3. In a tamping device for railway ties, an upright shaft adapted for longitudinal reciprocating movement, a supporting member adjacent to the lower end of said shaft, a pair of tamping blades pivotally supported on said member and having operating edges movable simultaneously to tamp beneath and at the sides of a tie and means operable by said shaft connected to said blades for imparting oscillating movement to said blades.

4. In a tamping device for railway ties, an upright shaft, a sleeve on the lower end of said shaft, a support for said sleeve, a pair of tamping blades pivotally connected to said sleeve and having operating edges movable simultaneously to tamp the road bed at opposite sides of a tie and means operable by said shaft for imparting oscillating movement to said blades.

5. In a tamping device for railway ties, an upright shaft adapted for longitudinal reciprocating movement, a shoe carried on the lower end of said shaft and adapted to rest upon a tie, a pair of tamping blades having operating edges simultaneously movable downward and toward each other beneath said tie and means operable by said shaft and connected to said blades for imparting oscillating movement to said blades.

6. In a tamping device for railway ties, an upright shaft adapted for longitudinal reciprocating movement, a sleeve on the lower end of said shaft, means for supporting said sleeve upon a tie to be tamped, a pair of tamping blades pivotally connected to said sleeve and having the operating edges movable downward at opposite sides of said tie, means operable by said shaft for imparting downward movement to said blades, said shaft being slideable longitudinally in said sleeve, and a spring arranged to raise said blades.

7. In a tamping device an upright shaft adapted for longitudinal reciprocating movement, a member upon the lower end of said shaft adapted to rest upon a relatively stationary support above the material to be tamped, a pair of tamping blades having operating edges simultaneously movable downward at opposite sides of said support and toggle members operable by said shaft and

connected to said blades for simultaneously operating said blades downward.

8. In a tamping device for railway ties, an upright shaft adapted for longitudinal reciprocating movement, a sleeve on the lower end of said shaft, resilient means for supporting said sleeve upon a tie to be tamped, a pair of tamping blades pivotally connected to said sleeve and having the operating edges movable downward and toward each other adjacent to opposite sides of said tie, toggle members operable by said shaft for imparting downward movement to said blades, said shaft being slidable longitudinally in said sleeve, and a spring arranged to raise said blades from downwardly extended position.

In testimony whereof, I have hereunto signed my name to this specification.

ERNEST E. PETERSON.
